[57] CLAIM

The ornamental design for a outdoor electrical outlet cover, as shown and described.

DESCRIPTION

FIG. 1 is a front and upper left perspective view showing our new design;

FIG. 2 is a left side view thereof the right side view thereof being a mirror image;

FIG. 3 is a front view thereof;

FIG. 4 is a rear view thereof;

FIG. 5 is a top view thereof;

FIG. 6 is a bottom view thereof;

FIG. 7 is a front and upper left perspective view showing a second embodiment of our design;

FIG. 8 is a left side view of the embodiment shown in FIG. 7;

FIG. 9 is a front view of the embodiment shown in FIG. 7;

FIG. 10 is a rear view of the embodiment shown in FIG. 7;

FIG. 11 is a top view of the embodiment shown in FIG. 7;

FIG. 12 is a bottom view of the embodiment shown in FIG. 7, and,

FIG. 13 is a front and lower right perspective view of the first embodiment.

FIG. 2

FIG. 1

FIG.3

FIG.4

FIG. 5

FIG. 6

FIG. 8

FIG. 7

FIG. 9

FIG. 10

FIG. 11

FIG. 12

FIG. 13
